UNITED STATES PATENT OFFICE.

CLARENCE BAILEY PORTER, OF PORTLAND, OREGON, ASSIGNOR TO J. C. ALLEN & CO., OF PORTLAND, OREGON, A CORPORATION OF OREGON.

PENCIL-PRINTING MACHINE.

No. 851,103.

Specification of Letters Patent.

Patented April 23, 1907.

Application filed December 22, 1905. Serial No. 292,959.

To all whom it may concern:

Be it known that I, CLARENCE BAILEY PORTER, a citizen of the United States, residing at Portland, in the county of Multnomah and State of Oregon, have invented a new and useful Improved Pencil-Printing Machine, of which the following is a specification.

This invention relates to a machine for printing pencils, the object being to provide a cheap, simple and efficient construction of hand operative machines, capable of quickly and easily imprinting one or more lines upon a wooden lead pencil, the complete operation being completed at one movement of the machine, irrespective of the number of lines printed upon the pencil.

The invention also has other objects in view, all of which are accomplished by the means herein shown and described, and pointed out in the claims.

In the drawings forming a part of this specification: Figure 1 is a top plan view of a pencil printing machine, constructed in accordance with my invention. Fig. 2 is a vertical sectional view of the same, the dotted lines showing the position of the parts at the completion of the printing operation. Fig. 3 is a top plan view of the bed-plate, and Fig. 4 is a detail perspective view showing one side of the hopper, the platen, the pencil feeding rods, and a portion of the inking roll.

In carrying out my invention, I employ a bed-plate A, which may be of any suitable size desired and at the forward end thereof is produced a recess A', into which a chase B, is inserted, the said chase carrying one or more lines of type B', and this chase is held in the recess at the forward end of the bed plate by means of the turn-button B². Just to the rear of the recess A', is a circular recess A², in which fits the inking disk C, having an integral shaft C', which extends through the opening A³, produced in the bed-plate, and carries a ratchet-wheel D, upon the lower end thereof, the purpose of which will appear hereinafter. The bed-plate is cut away upon opposite sides as shown at A⁴, providing longitudinal guideways at each side, and sliding upon the bed-plate in these guideways is the frame E, having laterally projecting handles E', which are grasped by the operator and the frame E, moved back and forth upon the bed-plate for the purpose of operating the pencil feeding and printing mechanisms.

The frame E, has an arm F, attached to one side thereof, and which embraces one edge of the bed-plate and extends thereunder as shown in dotted lines in Figs. 1 and 2, and the inner end of this arm is provided with a spring pawl G, which is adapted to engage the ratchet-wheel D, during each reciprocation of the frame E, and this engagement of the pawl with the ratchet-wheel serves to turn the inking disk C, step by step, and thereby uniformly distribute the ink to the inking roller H, journaled in slots H', produced in the sides of the frame E, and normally held in engagement with either the inking disk or type, by means of springs H², which are connected to the opposite ends of the platen and bear at their free ends upon the journals of the ink roller. It will be noticed that the roller is made the full width of the machine and the inking disk substantially the same width as the length of the roller, thereby permitting a maximum length of line to be printed upon the pencil. The platen I, is connected to the forward ends of the side members of the frame E, and the said side members are undercut as shown at E², beneath the platen I, the purpose of this undercut being to permit a pencil to be dropped beneath the platen and caused by said platen to travel over the face of the type during the forward movement of the frame as hereinafter more fully explained. The platen I, is covered upon the under side by means of a piece of fabric K, the ends of said fabric being connected to winding shafts K', passing through the sides of the frame and securely connected to the top of the platen by means of clip-plates K², secured by screws K³, said screws and plates being loosened when it is desired to unwind a portion of the fabric from one shaft and wind it upon the other, for the purpose of presenting a clean portion of fabric. The fabric covering of the platen, not only serves as a cushion, but it also prevents the slipping of the pencil and insures an even rotation of the pencil as it passes along under the platen and over the lines of type.

The pencils L, are carried in a hopper at the forward ends of the frame and are dropped in a horizontal position one at a time, the pencil being dropped just in advance of the platen when the frame reaches the limit of its rearward movement, and upon the forward movement of the frame the

pencil is caused to travel beneath the platen and over the line of type and in this manner receives the imprint upon the curved surface of the pencil, it being understood that my machine is intended to be used for printing round pencils only.

The hopper comprises the adjustable side-plates M, having slotted arms M', which slotted arms M', are connected to the rear 10 inclined guide-bars N, said guide-bars being connected at their lower ends to a forward cross bar O, which is attached to and connects the forward ends of the side members of the frame E. This front bar O, projects 15 laterally upon opposite sides of the machine, and is bent back upon itself at O', providing feedways directly beneath the ends of the side plates M, of the hopper and connected to the free ends of the return portion are the 20 front inclined guide-bars P, said bars N and P, serving to feed the pencils in proper order. Said bars converging toward each other as most clearly shown and the lower ends thereof extend in parallel relation as shown at N', 25 and P', and are spaced apart a sufficient distance to permit one pencil and one pencil only, to pass down through. By this it is meant that the pencils in passing down between the contracting or converging ends of 30 the guide-bars, rest one above the other as most clearly shown in Fig. 2.

For the purpose of feeding the pencils from the hopper, one at a time, I employ the upper cut-off rods R, and the lower cut-off rods 35 R', the forward ends of said rods working through openings produced in the front bar O, adjacent the guide-bars N, and O, and the rear ends of these rods are connected to the oppositely arranged arms R²—and R³, 40 carried by the rock-shaft R⁴, the spring S, connected thereto serving to hold the rock-shaft in such position that the lower cutoff rod R', will normally extend across the bottom of the hopper and hold the bottom pencil from dropping. When the frame is 45 pushed back to the full limit, a tripping arm T, carried by the rock-shaft R⁴, engages a stop T', projecting upwardly from the bed-plate and such movement forces the forward 50 end of the upper cut-off rods R, between the bottom pencil and the one next above and simultaneously draws the bottom rods R', rearwardly, so as to drop the bottom pencil directly in advance of the platen and the rear 55 of the chase.

In Fig. 2, I have shown in full lines the positions of the various parts when the frame and hopper have reached the limit of their rearward movements, and the bottom pencil 60 has just been dropped. Upon the return movement of the frame, the positions of the cut-off rods are reversed, and the pencil is caused to travel beneath the platen over the face of the type and beyond the forward end

of the bed plate, and in this manner is discharged from the machine. During this and the return movement the type are thoroughly inked and ready to make another imprint upon the next pencil which is dropped when the frame reaches the end of this rear movement.

It will thus be seen that I provide an exceedingly cheap, simple and efficient construction of hand-operative pencil printing machine, capable of printing one or more 75 lines upon the pencil at one time.

Having thus fully described my invention, what I claim as new and desire to secure by Letters Patent is:

1. In a pencil printing machine, the combination with a bed-plate provided with a chase and an inking disk, of a frame movable upon the bed-plate and carrying a hopper, a platen also carried by the frame having its under side covered with fabric, and means for feeding the pencils from the hopper, one at a time, and causing them to travel over the chase and under said platen, as set forth.

2. In a pencil printing machine, the combination with the bed-plate carrying the chase and ink-disk, a reciprocating frame carrying a platen, inking roller, pencil hopper, cut-off rods, and means for operating the cut-off rods as specified.

3. In a pencil printing machine, the combination with the bed-plate carrying a chase, of a reciprocating frame, a platen carried by the frame winding shafts mounted on said platen carrying a strip of fabric extending 100 over the under side of said platen, the forward ends of the frame being undercut as specified.

4. In a pencil printing machine, the combination with the bed-plate, having the chase, inking disk, and stop, of the reciprocating frame, the inking roll, the platen, the hopper, comprising the converging guide-bars and adjustable end plates, the upper and lower cut-off rods, the rock shaft to which the rods are connected, the spring connected to said shaft, the tripping arm connected also to the shaft, the operating handles connected to the frame, and means for rotating the ink disk, substantially as described.

5. In a pencil printing machine, the combination with the bed plate carrying a chase and ink-disk, of a reciprocating frame mounted on said bed plate carrying a platen, inking roller and pencil hopper, cut off rods carried by said frame adapted to extend under the mouth of the hopper, and means for operating said rods and ink-disk for the purpose described.

CLARENCE BAILEY PORTER.
